UNITED STATES PATENT OFFICE.

CHARLES F. PYM, OF LYNN, MASSACHUSETTS, ASSIGNOR TO UNITED SHOE MANUFACTURING CORPORATION, OF PATERSON, NEW JERSEY, A CORPORATION OF NEW JERSEY.

END-LASTING MECHANISM.

Application filed December 19, 1918, Serial No. 267,504. Renewed October 20, 1922. Serial No. 595,845.

To all whom it may concern:

Be it known that I, CHARLES F. PYM, a subject of the King of England, residing at Lynn, in the county of Essex and State of Massachusetts, have invented certain Improvements in End-Lasting Mechanisms, of which the following description, in connection with the accompanying drawings, is a specification, like reference characters on the drawings indicating like parts in the several figures.

This invention relates to machines for working uppers over lasts, and more particularly to mechanism for lasting the end portion of a shoe. The invention is herein shown as embodied in end lasting mechanism particularly designed for use in a machine for pulling over a shoe and for lasting the toe portion of the shoe; but it will be understood that the invention, in its broader aspects, is not restricted in utility to machines for performing both pulling-over and lasting operations nor to machines in which the lasting mechanism is specifically designed for toe lasting.

An important object, among others, of the present invention is to provide in machines of the above mentioned class improved lasting mechanism of such construction as to insure more accurate conformity than heretofore to the varying contours of different shoes and to render the same mechanism capable of successful use upon a wide range of styles and sizes of shoes. With these and other ends in view, a feature of the invention consists in a novel construction and arrangement of end lasting mechanism in which a plurality of over-working members are arranged to operate at the same side of the longitudinal median line of a shoe and are relatively movable into conforming relation to the contour of the shoe, together with operating means for rendering each member effective to work firmly into lasted position that portion of the upper upon which it operates. The construction herein shown comprises end embracing wipers the opposite halves of which are sectional, with operating mechanism connected to the different sections and so constructed as to impart closing movement over the shoe to each section individually, with provision for relative movement of different portions of the operating mechanism through compensating connections in such manner as to ac-

celerate the movement of one section when the movement of another section is retarded or stopped by reason, for example, of the resistance of the shoe materials. By the use of such mechanism the margin of the upper will be wiped in closely against the shoulder or rib of the sole or insole along the entire length of the portion of the margin under treatment without danger of wiping too far inward or of applying undue pressure at any portion of the shoe with consequent danger of breaking down the rib or of otherwise damaging the sole or insole.

The construction herein shown includes means for applying a binder to the shoe to hold the upper in lasted position and for forcing the ends of the binder into the shoe materials to anchor the binder in place, the illustrative construction thus involving features of the invention disclosed in Letters Patent No. 1,436,194 granted upon my application on Nov. 21, 1922; and in a further aspect the present invention involves features of novelty in the binder applying means, some of which are related to wiping mechanism of the novel construction above described, while other features are independent of the particular construction of the means employed for working the upper into lasted position.

The above and other features of the invention, including also a novel organization for substantially equalizing the pressures of different wiper members on a shoe and certain details of construction and combinations of parts, will now be more particularly described with reference to the accompanying drawings and pointed out in the claims.

In the drawings:

Figure 1 is a plan view of toe lasting mechanism in which the invention is embodied, portions of the mechanism being broken away to illustrate the interior construction;

Fig. 2 is a view in side elevation of the mechanism shown in Fig. 1 as it appears when mounted on a machine of the illustrative type;

Fig. 3 is a view in elevation, looking inward toward the intermediate portion of the wipers;

Fig. 4 is a section on the line 4—4 of Fig. 1; and

Fig. 5 is a section on the line 5—5 of Fig. 1.

The invention is herein shown for purposes of illustration as embodied in mechanism designed for use in a machine of the type shown in the patent hereinbefore referred to, comprising a front arm 2 shown in section in Fig. 1 and fragmentarily in side elevation in Fig. 2, this arm being mounted for operative swinging movement lengthwise of a shoe positioned for toe lasting, as fully explained in said patent. Mounted on the arm 2 is a wiper supporting block 4 suitably recessed to provide a guideway for a pair of wiper supporting gear segments 6 upon which the wipers are adjustably secured. The wipers, in accordance with the illustrative embodiment of this invention, comprise a pair of end plates 8 connected by a pivot stud 10 arranged to be located substantially midway between the opposite sides of the shoe upon which the wipers are to operate and coinciding with the axes of the gear segments 6, the plates 8 thus being mounted for relative closing movements over the margin of the sole or insole at the end of the shoe. Mounted on pivots 12 on the wiper plates 8 at opposite sides of the center pivot 10 are additional wiper plates 14 which are arranged to serve in effect as continuations of the end plates and to operate upon portions of the margin of the upper extending beyond the ends of the plates 8 along the opposite sides of the toe portion of the shoe. The inner or wiping edges of the different wiper sections 8 and 14 are curved in substantial conformity to the curve of the edge of the shoe bottom, or the corresponding curve of the shoulder or rib of the sole or insole, the provision for relative movement of each plate 8 and the connected plate 14 about the pivot 12 permitting a variation in the relation between these plates conformable to the varying edge contours of shoes of different shapes and sizes.

For imparting operative closing movement to the wipers, the wiper support 4 carries pinions 16 arranged respectively to engage the teeth of the opposite gear segments 6, and pinions 18 operatively connected to sliding rack bars 20 which are connected at their inner ends by means of links 22 to the side or extension wiper plates or sections 14. For imparting operative movement to the pinions 16 and 18 the support 4 carries sliding rack bars 24 and 26 arranged respectively in operative engagement with said different pinions, the outer ends of each pair of rack bars 24 and 26 being connected together by means of a transverse cross-bar or link 28, the connections between this link and the rack bars being so constructed as to afford sufficient play to provide for relative lengthwise movement of the different rack bars. Pivotally connected to each link 28 between the

opposite ends of the link is an operating rod 30, these rods in the present construction being supported and guided in the lower ends of members 32 which may be pivotally mounted on the machine substantially as described in the patent above referred to, to serve as means to render the wiper closing mechanism operative at a definite point in the bodily movement of the wipers toward the shoe. Mounted on the rods 30 are springs 34 bearing at their inner ends on the members 32 and at their outer ends on adjustable nuts 36 on the rods, the springs 34 thus tending to hold the members 32 in engagement with stop shoulders 38 on the inner end portions of the rods. It will be understood that, as explained in said patent, the movement of the arm 2 and its supported wiper mechanism toward the shoe carries the members 32 into engagement with stops independently adjustable with respect to each member to determine the time when closing movement of the respective opposite side portions of the wipers shall begin. Springs 40 connected to the members 32 and to pins 42 on the support 4 are arranged to assist in the return of the parts to starting position in substantially the same manner as in the construction of my prior patent.

In the operation of the construction as thus far described, the members 32, when their movement toward the shoe is stopped as above explained, are rendered operative through the springs 34 to stop lengthwise movement toward the shoe of the rods 30 and the connected rack bars 24 and 26. As the support 4 continues its movement toward the shoe these bars are thus rendered effective to impart turning movement to the pinions 16 and 18 in such direction as to operate the gear segments 6 and the rack bars 20 respectively for swinging the different wiper sections simultaneously about their pivots 10 and 12 to close them round the end of the shoe and to wipe the margin of the upper inward over the feather of the sole or insole. If one or the other of the sections 8 or 14 at either side of the shoe during this movement encounters greater resistance than its connected sections its movement may in consequence be retarded or stopped temporarily and the movement of the connected section will be accelerated by reason of the compensating or equalizing connection 28 between the rack bars 24 and 26, and as soon as the resistances are again substantially equalized, the different wiper sections will continue their inward closing movements together at normal relative rates of speed. Similarly, by reason of the equalizing connection between the rack bars, if either of the respective wiper sections arrives earlier than the other in position to force the margin of the upper firmly against the shoulder or rib of

the sole or insole, its inward closing movement will be substantially stopped and the movement of the other wiper section will be accelerated until it also arrives substantially at the proper limit of its overwiping movement during the continued movement of the wiper mechanism as a whole lengthwise of the shoe, thereby substantially equalizing the pressures of the different wiper members on the shoe. In case both wiper sections 8 and 14 at one side of the mechanism complete their overwiping movement laterally of the shoe earlier than the sections on the opposite side, the construction further affords provision for yield of one or the other of the springs 34 to permit the wiping over operation at the opposite side of the shoe to be completed, in a manner similar to the construction of my prior patent.

As hereinbefore stated, the construction shown includes means for applying a binder to the shoe for holding the upper in lasted position and for forcing projecting portions, such as inturned ends, of the binder into the shoe materials to anchor the binder in place. For this purpose, in the present construction, each of the wiper sections 14 is provided with a driver plate 44 pivoted on the same stud 12 as the wiper section, said plate, which is of substantially the same thickness as the binder, having its lower surface substantially flush with the lower over-wiping surface of the end wiper sections 8, as shown in Fig. 3. The plate 44, as thus mounted, is positioned between the wiper section 14 and a plate 46 which is secured at its ends to the section 14 and is recessed on its upper side between its ends to provide a space in which the driver plate may swing freely. Springs 48 connected to the plates 44 and to the supporting block 4 are arranged to hold the driver plates normally in retracted position as shown in Fig. 1. When the plates are thus retracted a space is provided in front of the inner edge of each plate 44 and between the section 14 and the underlying plate 46 to receive the end portion of a wire binder *a*, thus permitting the plates 46 to support the ends of the binder in position to be applied to the shoe. As the binder is thus supported, its intermediate portion extends in front of the inner edges of the end wiper plates 8 which, as above explained and as shown in Fig. 3, extend downward farther than the plates 14 a distance substantially equal to the thickness of the driver plates 44 and of the binder. In order to assist in supporting this intermediate portion of the binder, the wiper sections 8 are each provided with a plunger 50 normally held by a spring 52 with its end projecting beyond the front edge of the plate 8 in position to support the binder when the latter is inserted in the wiper mechanism. As thus positioned the plungers 50 are arranged to engage the end face of the shoe in the operative forward movement of the wipers, the springs 52 then yielding to permit the wipers to close over the shoe. It will be evident that in the operation of this construction the intermediate portion of the binder is forced inwardly over the feather of the sole or insole ahead of the wiper plates 8 and by the action of these plates, portions of the binder which are indicated in dotted lines in Fig. 1 as located back of the front edges of the side wiper plates 14 remaining in substantially the same relation to the edges of these plates under the control of the driver plates 44 which are moved inwardly with the plates 14 in the operation of the latter, until the overwiping operation has been substantially completed.

In the construction shown the end wiper plates 8 are undercut, as indicated in Fig. 4 and by dotted lines in Fig. 1, to provide abutment faces 54 curved in substantially parallel relation to the front edges of the plates and spaced backwardly from the edges a distance substantially equal to the width of the feather of the sole or insole, the plungers 50 being mounted in these undercut portions. In operation the abutment faces 54 are thus carried into engagement with the end face of the shoe when the wipers have substantially completed their over-wiping movement, and such faces may serve by engagement with the shoe to limit the operative movement of these wiper plates and the movement of the wiper mechanism lengthwise of the shoe, as well as to assist in forming the upper along the edge of the shoe bottom. A similar function is performed for the wiper sections 14 by the plates 46, the front faces of which are curved similarly to the front edges of these plates and are arranged to engage the lateral periphery of the shoe similarly to the abutment faces 54 on the end plates. The construction thus affords provision for relative movement between the parts which engage the lateral periphery of the shoe as well as, and in substantially the same manner as, the different wiper sections, insuring thereby that the lateral periphery of the shoe shall be closely embraced along the length of the portion of the shoe upon which the wiper mechanism is operative to assist in shaping the shoe as well as to guide the binder into its proper relation to the shoe and to limit the movement of the wipers.

For operating the driver plates 44 the machine is provided with driver members 56 pivotally mounted on the wiper support in position to engage the plates and force them inward against the tension of the springs 48, these members being operated

through gearing 58 from crank arms 60 in a manner substantially as explained in my prior patent. This mechanism is operated when the overwiping movement of the wiper plates has been substantially completed, to force the binder closely into the angle between the feather and the rib of the sole or insole along the opposite sides of the shoe and to force the inturned ends of the 10 binder into the shoe materials in directions substantially parallel to the plane of the shoe bottom to anchor the binder in place. It will be understood that the plates 44 in their inward movement have also a supplemental overwiping action on the shoe upper in the same plane as the lower faces of the end plates 8.

Having described the invention, what I claim as new and desire to secure by Letters Patent of the United States is:

1. Mechanism of the class described comprising, in combination, wiper members relatively movable to wipe the margin of an upper inward about the end of a shoe, other 25 wiper members arranged to operate upon portions of the upper extending along the sides of the shoe beyond said end wiper members, the side members being movable relatively to the end members in the over- 30 wiping operation about axes substantially perpendicular to the plane of the shoe bottom into substantial conformity to the curve of the shoulder or rib of the sole or insole, and wiper operating means having different 35 wiper operating portions arranged respectively in operative relation to the end members and the side members and connected for operative movements in time relation to close said members inward laterally of the shoe.

2. Mechanism of the class described comprising, in combination, end wiper plates, side wiper plates arranged to extend along the edge of the shoe bottom beyond said end plates, the end plates being mounted to 45 swing each about an axis transverse to the plane of the shoe bottom and the side plates being mounted to swing about other axes transverse to said plane into substantial conformity to the curve of the shoulder or rib 50 of the sole or insole, and operating means separately connected to said end plates and side plates respectively to close them over the shoe about said axes.

3. Mechanism of the class described comprising, in combination, end wiper plates, gear segments to which said end plates are connected for relative closing movements, pinions for operating said gear segments, side wiper plates arranged to extend along 55 the edge of the shoe bottom beyond said end plates and movable relatively to the end plates about axes transverse to the plane of the shoe bottom, additional pinions connected to the side plates, and means for imparting operative movements to said pinions.

to close the end plates and the side plates over the shoe.

4. Mechanism of the class described comprising, in combination, end wiper plates, gear segments to which said end plates are 60 connected, for relative closing movements, pinions for operating said gear segments, side wiper plates arranged to extend along the edge of the shoe bottom beyond said end plates and movable relatively to the end plates, rack bars connected to said side plates, pinions engaging said rack bars, and operating rack bars connected respectively to the different pinions for imparting closing movement to the end plates and the 65 side plates.

5. Mechanism of the class described comprising, in combination, a wiper support mounted for movement lengthwise of a shoe toward the end of the shoe, end wiper plates carried by said support, side wiper plates also carried by said support and arranged to extend along the edge of the shoe bottom beyond said end plates, said side wiper plates being movable relatively to the 70 end plates, and means separately connected to said end plates and side plates and operated by a movement of the wiper support toward the shoe for closing the several 75 side plates.

6. Mechanism of the class described comprising, in combination, a wiper support mounted for movement toward the end of a shoe, end wiper plates and side wiper plates carried by said support and mounted for 80 closing movement over the shoe with provision for relative movement between the end plates and the side plates, pinions connected to the end plates to close them, other 85 pinions connected to the side plates, and rack bars arranged to be rendered operative upon a movement of the support toward the shoe for turning said pinions to close the several 90 wiper plates over the shoe.

7. Mechanism of the class described comprising, in combination, end wiper plates each mounted to swing about an axis at the end of a shoe, side wiper plates pivotally mounted on said end plates and arranged to extend along the edge of the shoe bottom beyond the end plates, and operating means comprising different members arranged respectively in operative relation to the end plates and the side plates and operatively connected to close said different plates inward laterally of the shoe in time relation to one another.

8. Mechanism of the class described comprising, in combination, end wiper plates each mounted to swing about an axis at the end of a shoe, pinions connected to said end plates to operate them, side plates pivotally mounted on said end plates and arranged to extend along the edge of the shoe bottom beyond the end plates, other pinions 110

connected to the side plates to operate them, and means for turning the several pinions to swing the end plates and the side plates inward over the shoe.

5 9. Mechanism of the class described comprising, in combination, a plurality of wiper members pivoted together and arranged to extend in a series along each side of the end portion of a shoe, and operating means 70 comprising parts separately connected respectively to the different wiper members and movable to swing said members inward over the shoe.

10 10. Mechanism of the class described comprising, in combination, sectional end embracing wipers constructed to present a plurality of sections arranged in order lengthwise of the edge of the shoe bottom at each side of the longitudinal median line 75 of the shoe, and operating means separately connected to each section for closing the wipers inward over the shoe and constructed to permit relative movements of the different sections along the plane of the shoe bottom in response to resistance of the shoe materials.

15 11. In mechanism of the class described, the combination with wiper members mounted for closing movements at the opposite 80 sides of the end portion of a shoe, of rack bars for imparting closing movements to said members, links connecting said rack bars to the wiper members, pinions engaging said rack bars, and means for imparting 85 turning movement to said pinions to operate the wiper members.

20 12. Mechanism of the class described comprising, in combination, end wiper plates, side wiper plates arranged to extend along 90 the edge of the shoe bottom beyond said end plates and movable relatively to the end plates, and operating means separately connected to the end plates and the side plates to close them over the shoe and constructed 100 and arranged to permit relative movement between the end plates and the side plates in response to differences in resistance encountered by the respective plates.

25 13. Mechanism of the class described comprising, in combination, a plurality of wiper members arranged to extend in a series along each side of the end portion of a shoe and mounted for relative closing movements over 105 the shoe, and means for operating said wiper members, said operating means being constructed and arranged to accelerate the movement of one of the wiper members in consequence of resistance encountered by another of the members in its closing movement.

30 14. Mechanism of the class described comprising, in combination, end wiper plates, side wiper plates arranged to extend along 110 the edge of the shoe bottom beyond said

end plates and movable relatively to the end plates along the plane of the shoe bottom to permit the several plates to be closed into substantial conformity to the curve of the shoulder or rib of the sole or insole, and operating means separately connected to the end plates and the side plates, said operating means being constructed and arranged to close the several plates yieldingly over the shoe and to continue the closing movement 75 of one or more of the plates if movement of another of the plates is stopped by resistance of the shoe materials.

15 15. Mechanism of the class described comprising, in combination, end wiper plates 80 mounted for relative closing movements over a shoe, side wiper plates arranged to extend along the edge of the shoe bottom beyond said end plates and movable relatively to the end plates, and operating means comprising 85 different members connected respectively to the end plates and the side plates to close them and equalizing connections between the different members to permit relative movement between the end plates and the side 90 plates in response to differences in resistance encountered by the respective plates.

16 16. Mechanism of the class described comprising, in combination, end wiper plates mounted for relative closing movements over 95 a shoe, side wiper plates arranged to extend along the edge of the shoe bottom beyond said end plates and movable relatively to the end plates, a pinion connected to each of said plates for operating it, a rack bar engaging each pinion, and means for rendering said rack bars effective to operate the pinions comprising an equalizing connection between the rack bars at each side of the mechanism to permit relative movement between the end plates and the side plates in 105 response to differences in resistance encountered by the respective plates.

17 17. Mechanism of the class described comprising, in combination, end wiper plates 110 mounted for relative closing movements over a shoe, side wiper plates arranged to extend along the edge of the shoe bottom beyond said end plates and movable relatively to the end plates, pinions connected respectively to 115 the different wiper plates to operate them, rack bars connected respectively to the different pinions, a cross bar connected to the rack bars at each side of the wiper mechanism and arranged to permit relative movement between said rack bars, and operating means connected to said cross bars between 120 their connections to the rack bars to render said rack bars effective for imparting wiper closing movements to the pinions.

18 18. Mechanism of the class described comprising, in combination, sectional end embracing wipers constructed and arranged to present a plurality of wiper sections positioned one in advance of another along 130

the edge of the shoe bottom on the same side of the longitudinal median line of the shoe and relatively movable into substantial conformity to the curve of the shoulder 5 or rib of the sole or insole, a pinion connected to each of said sections to operate it, a pair of rack bars connected respectively to the different pinions, a cross bar connected at its opposite ends to said rack bars 10 and arranged to permit relative movement between the rack bars, and operating means connected to said cross bar at a point between its opposite ends and arranged to control said cross bar yieldingly to render 15 the rack bars effective for imparting wiper closing movement to the pinions.

19. Mechanism of the class described comprising, in combination, end wiper plates mounted for relative closing movements 20 over a shoe, side wiper plates arranged to extend along the edge of the shoe bottom beyond said end plates and movable relatively to the end plates, means for operating said wiper plates, means for positioning 25 a shoe binder with its intermediate portion in advance of the front edges of said end plates to cause it to be forced into holding relation to the materials at the end of the shoe by the operative movement of the wipers, and additional means for forcing the binder into holding relation to the shoe materials 30 at the opposite sides of the shoe beyond the range of action of said end plates.

20. Mechanism of the class described comprising, in combination, end wiper plates mounted for relative closing movement over a shoe, side wiper plates arranged to extend along the edge of the shoe bottom beyond 40 said end plates and movable relatively to the end plates, means for operating said wiper plates, means for positioning a shoe binder with its intermediate portion in advance of the front edges of said end plates 45 to cause it to be forced into holding relation to the shoe materials at the end of the shoe by the action of said plates and with portions of the binder which extend beyond the end plates retracted from the front edges of the side plates, and means for forcing the binder into holding relation to the shoe materials on the opposite sides of the shoe and for driving the ends of the binder into the shoe to anchor the binder in place. 50

21. Mechanism of the class described comprising, in combination, end wiper plates mounted for relative closing movements over a shoe, side wiper plates arranged to extend along the edge of the shoe bottom 55 beyond said end plates and movable relatively to the end plates, means for supporting adjacent to the wiper plates a wire binder having inturned ends, and driver plates arranged to extend substantially from said end plates rearwardly along the sides 60

of the shoe for forcing the inturned ends of the binder into the shoe.

22. Mechanism of the class described comprising, in combination, end wiper plates mounted for relative closing movements 70 over a shoe, side wiper plates pivoted on said end plates and arranged to extend along the edge of the shoe bottom beyond the end plates, means for supporting adjacent to said wiper plates a wire binder having inturned ends, and driver plates mounted to swing about the same axes as the side plates for forcing the inturned ends of the binder into the shoe. 75

23. Mechanism of the class described comprising, in combination, end wiper plates mounted for relative closing movements over a shoe, side wiper plates arranged to extend along the edge of the shoe bottom beyond said end plates and movable relatively to the end plates, said side plates being arranged with their overwiping faces spaced from the plane of the overwiping faces of the end plates a distance substantially equal to the thickness of a shoe 80 binder, means for positioning a shoe binder having inturned ends with its intermediate portion in advance of the front edges of the end plates and with its end portions substantially contiguous to the overwiping 85 faces of the side plates, and driver plates mounted for movement in substantially contiguous relation to the overwiping faces of the side plates for forcing the ends of the binder into the shoe. 90

24. Mechanism of the class described comprising, in combination, end wiper plates mounted for relative closing movements over a shoe, side wiper plates arranged to extend along the edge of the shoe bottom beyond 105 said end plates and movable relatively to the end plates, means carried by the side plates for supporting the end portions of a shoe binder in position to be applied to the shoe, and means carried by the end plates 110 for supporting the intermediate portion of the binder. 110

25. Mechanism of the class described comprising, in combination, end wiper plates mounted for relative closing movements 115 over a shoe, side wiper plates arranged to extend along the edge of the shoe bottom beyond said end plates and movable relatively to the end plates, means carried by the side plates for supporting the end portions of a 120 binder in position to be applied to the shoe, and a spring controlled member on each of the end plates arranged to support the intermediate portion of the binder and to yield upon engagement with the shoe to permit the 125 wipers to close over the shoe.

26. Mechanism of the class described comprising, in combination, end wiper plates mounted for relative closing movements over a shoe, side wiper plates arranged to ex- 130

5 tend along the edge of the shoe bottom beyond said end plates and movable relatively to the end plates, means fast on the side plates for supporting the opposite end portions of a shoe binder in position to be applied to the shoe with said end portions initially retracted from the front edges of said plates, and means for supporting the intermediate portion of the binder in advance of 10 the front edges of the end plates, said last-named means being yieldable upon engagement with the shoe to permit the wipers to close over the shoe.

15 27. In mechanism of the class described, the combination with end embracing wipers comprising relatively movable sections at each side of the end of a shoe, of means for positioning a shoe binder adjacent to the wipers, said means comprising a spring controlled member carried by one of the wiper sections and arranged to yield upon engagement with the shoe to permit the wipers to close over the shoe.

20 28. Mechanism of the class described comprising, in combination, sectional end embracing wipers constructed and arranged to present a plurality of wiper sections at each side of the longitudinal median line of the shoe, the different sections at each side being mounted to swing relatively about axes transverse to the plane of the shoe bottom for wiping the margin of an upper inwardly, and means on each wiper section constructed and arranged to engage the lateral periphery 30 of the shoe in substantial conformity to the edge contour of the shoe.

25 29. Mechanism of the class described comprising, in combination, sectional end embracing wipers constructed and arranged to present a plurality of relatively movable wiper sections at each side of the longitudinal median line of the shoe, means for imparting closing movement to said wipers constructed and arranged to cause the movement of one or more of the wiper sections to continue if movement of another section is stopped by resistance of the shoe materials, and means on each wiper section arranged to engage the lateral periphery of the shoe to 40 limit its closing movement over the shoe.

30 30. Mechanism of the class described comprising, in combination, end wiper plates mounted for relative closing movements over a shoe, side wiper plates arranged to extend 45 along the edge of the shoe bottom beyond said end plates and movable relatively to the end plates, and means for imparting operative closing movements to said end plates and side plates, each of the end plates and the side plates having fast thereon means for engaging the lateral periphery of the shoe to limit the overwiping movements of the respective plates.

35 31. Mechanism of the class described comprising, in combination, end wiper plates

50 mounted for relative closing movements over a shoe, side wiper plates arranged to extend along the edge of the shoe bottom beyond said end plates and movable relatively to the end plates, means for imparting operative closing movements to said end plates and side plates, and means fast on the side plates for engaging the lateral periphery of the shoe to limit closing movement of said plates, said limiting means being constructed 55 and arranged to support the end portions of a shoe binder in position to be applied to the shoe.

55 32. Mechanism of the class described comprising, in combination, end wiper plates 60 mounted for relative closing movements over a shoe, side wiper plates arranged to extend along the edge of the shoe bottom beyond said end plates and movable relatively to the end plates, means for imparting operative 65 closing movements to said end plates and side plates, members secured on the lower faces of said side plates and constructed to engage the lateral periphery of the shoe to limit the closing movements of said plates, 70 said members having portions spaced from the side plates a distance substantially equal to the thickness of a shoe binder to permit the end portions of the binder to be supported on the members, and driver members 75 mounted for movement between the side plates and said supporting members for forcing the binder into holding relation to the shoe.

80 33. In mechanism of the class described, 100 end embracing wipers having the overwiping faces of their outer end portions offset from the overwiping face of the intermediate portion to admit the ends of a wire binder which extends in front of said intermediate portion of the wipers, and members mounted for movement along said offset faces to force the end portions of the binder inwardly against the shoe.

85 34. In mechanism of the class described, 105 end embracing wipers having means for supporting a binder in front of the intermediate portion of their overwiping edges and having the overwiping faces of their outer end portions offset from the overwiping face of 110 said intermediate portion to admit the ends of the binder, members secured to the wipers to support the ends of the binder adjacent to said offset faces, and driver plates movable between said members and the wipers 115 to force the ends of the binder into the shoe.

90 35. In mechanism of the class described, 120 end embracing wipers having an undercut portion to provide an abutment face for engagement with the lateral periphery of a shoe, and means comprising a spring plunger mounted in said undercut portion of the wipers to support a binder in front of the overwiping edges of the wipers.

95 36. In mechanism of the class described, 125

end embracing wipers arranged to engage an upper on a substantially continuous line round the end of a shoe from one side to the other and comprising at each side of the 5 longitudinal median line of the shoe, a plurality of wiper sections relatively movable inwardly over the shoe about axes transverse to the plane of the shoe bottom and disposed substantially at the front ends 10 of the respective sections, and wiper operating means comprising parts connected respectively to the different wiper sections at each side and relatively movable in response to differences in resistance to the inward 15 movements of the different wiper sections.

37. In mechanism of the class described, end embracing wipers comprising wiper sections arranged to extend in a series round the end of a shoe and including a plurality 20 of sections at each side of the longitudinal median line of the shoe mounted for relative movement inwardly over the shoe, a plurality of operating members connected respectively to the different wiper sections at 25 each side of the longitudinal median line of the shoe, and movable compensating connections between said different members to permit relative movement of the sections at each side of the shoe in response to differences 30 in resistance encountered by the different sections in their overwiping movement.

38. In mechanism of the class described, end embracing wipers comprising wiper sections arranged to extend in a series round the end of a shoe and including a plurality 35 of sections at each side of the longitudinal median line of the shoe, the sections at each side being mounted to swing relatively 40 about axes transverse to the plane of the shoe bottom, a rack and pinion device for each of said sections to swing it inwardly over the shoe, and compensating connections between the different devices at each 45 side of the mechanism to permit relative movement of the different sections in response to differences in resistance encountered in the overwiping operation.

39. In mechanism of the class described, 50 end embracing wipers comprising wiper sections arranged to extend in a series round the end of a shoe and including a plurality 55 of sections at each side of the longitudinal median line of the shoe, the sections at each side being relatively movable in the overwiping operation about axes transverse to the plane of the shoe bottom, an operating member for each side portion of the mechanism, and separate connections 60 between each of said members and the different corresponding wiper sections comprising parts relatively movable in response to differences in resistance encountered by 65 said different sections in the overwiping operation.

40. In mechanism of the class described, end embracing wipers comprising wiper sections arranged to extend in a series round the end of a shoe with a plurality of sections at each side of the longitudinal median 70 line of the shoe, the different sections at each side being mounted for relative swinging movements laterally of the shoe, a support for said wipers movable to carry them lengthwise of the shoe, and operating means for 75 closing the wipers inward laterally of the shoe including a member at each side of the mechanism relatively to which said wiper support is movable, and connections between said members and the different respective 80 wiper sections at the corresponding sides of the mechanism including compensating devices to permit relative movement of the different wiper sections at each side in response to differences in resistance 85 encountered in the overwiping operation.

41. In mechanism of the class described, end embracing wipers comprising a plurality of wiper sections arranged to extend in a series round the end of a shoe 90 with a plurality of sections at each side of the longitudinal median line of the shoe, the different sections at each side being relatively movable laterally of the shoe in the overwiping operation, a wiper support movable to carry said wipers lengthwise of the shoe, a plurality of pinions on said support connected to the different wiper sections, rack bars engaging the different respective pinions, a cross-link between the 100 rack bars at each side of the mechanism, operating rods connected respectively to the different links, and means yieldingly connected to said rods to render the rods operative through movement of the wiper support to impart lateral swinging movements to the different wiper sections. 105

42. In mechanism of the class described, end embracing wipers comprising a plurality of relatively movable wiper members, 110 a wiper support movable to carry said members lengthwise of a shoe, operating members connected respectively to the different wiper members, an equalizer between said operating members permitting them to 115 move relatively in response to differences in resistance encountered by the different wiper members, and means acting through said equalizer to render said operating members effective to close the wiper members inwardly over the shoe in response to movement of the wiper support lengthwise of the shoe. 120

43. In mechanism of the class described, end embracing wipers comprising a plurality of relatively movable wiper members, 125 a wiper support movable to carry said members lengthwise of a shoe, and operating means for imparting to said wiper members closing movements inwardly over the shoe 130

in response to movement of said support lengthwise of the shoe comprising an equalizing connection between said different members responsive to differences in resistance encountered by said members substantially to equalize the pressures of the different members upon the shoe.

44. In mechanism of the class described, end embracing wipers comprising a plurality of relatively movable wiper members, pinions connected to said wiper members to close them inwardly over a shoe, rack bars

connected respectively to the different pinions to operate them, and controlling means for said rack bars comprising an equalizing connection between said bars operative in response to differences in resistance encountered by the different wiper members substantially to equalize the pressures of said members upon the shoe.

In testimony whereof I have signed my name to this specification.

CHARLES F. PYM.
